UNITED STATES PATENT OFFICE.

HENRY G. THOMPSON, OF NEW HAVEN, CONNECTICUT, ASSIGNOR TO THE
NEW HAVEN NOVELTY MACHINE COMPANY, OF SAME PLACE.

DESIGN FOR A PIPE-COUPLING.

SPECIFICATION forming part of Design No. 33,371, dated October 16, 1900:

Application filed July 28, 1900. Serial No. 25,203. Term of patent 14 years.

To all whom it may concern:

Be it known that I, HENRY G. THOMPSON, a citizen of the United States, residing at New Haven, county of New Haven, and State of Connecticut, have invented and produced a new, useful, and original Design for a Pipe-Coupling, of which the following is a specification, reference being had to the accompanying drawings, forming a part thereof.

Figure 1 is a perspective view of a pipe-coupling, illustrating my design; and Fig. 2 is a side elevation thereof.

As shown in the drawings, the leading feature of my design consists in a pipe-coupling the body of which has at one end a peripherally-grooved disk-like portion provided with a centrally-located tapering boss on its outer face and at the opposite end of the body a polygonal portion having a slightly-tapered spirally-grooved projection extended centrally from the polygonal portion.

The body of the pipe-coupling has at one end a disk-like portion b , peripherally grooved at b' and having a centrally-located tapering boss b^2 on its outer face, the other end of the case having a polygonal portion c , provided with a projection c' , extended centrally therefrom and spirally grooved, as at c^2 .

Having fully described my design, what I claim, and desire to secure by Letters Patent, is—

The design for a pipe-coupling, substantially as herein shown and described.

In testimony whereof I have signed my name to this specification in the presence of two subscribing witnesses.

HENRY G. THOMPSON.
